(57) CLAIM

The ornamental design for an electric hair clipper, as shown and described.

DESCRIPTION

FIG. 1 is a front, right and top perspective view of an electric hair clipper, showing my design.

FIG. 2 is a rear, left and bottom perspective view thereof.

FIG. 3 is a rear, left and top perspective view thereof.

FIG. 4 is a front elevation view thereof.

FIG. 5 is a rear elevation view thereof.

FIG. 6 is a left side elevation view thereof.

FIG. 7 is a right side elevation view thereof.

FIG. 8 is a top plan view thereof.

FIG. 9 is a bottom plan view thereof.

FIG. 10 is a front, right and top perspective view of detail 10 of FIG. 1, shown enlarged for clarity of disclosure.

FIG. 11 is a rear, left and top perspective view of detail 11 of FIG. 3, shown enlarged for clarity of disclosure; and, FIG. 12 is a front, right and top perspective view of the electric hair clipper, shown in condition of use for clarity of disclosure.

The broken lines depict portions of the electric hair clipper that form no part of the claimed design. The dot-dash broken lines in FIGS. 1, 3, 10, and 11 depict the boundaries of the enlargements that form no part of the claimed design.

1 Claim, 12 Drawing Sheets
